[57] CLAIM

The ornamental design for a golf swing practice mat, as shown and described.

DESCRIPTION

FIG. 1 is a top, right side perspective view of a golf swing practice mat, showing my new design;

FIG. 2 is a top plan view thereof;

FIG. 3 is a rear end elevational view, thereof;

FIG. 4 is a front end elevational view, thereof;

FIG. 5 is a right side elevational view, thereof, the left side being a mirror image; and,

FIG. 6 is a bottom plan view, thereof.
